JET ENGINE CONTAINER

William W. Higbee, Xenia, Ohio

Application November 14, 1951, Serial No. 256,355

4 Claims. (CL 206—46)

(Granted under the act of March 3, 1883, as
amended April 30, 1928; 370 O. G. 757)

1

The invention described herein may be manufactured and used by or for the United States Government for governmental purposes without payment to me of any royalty.

This invention relates to a jet engine container suitable for supporting and protecting the engine while in transit or storage or at any time prior to installation on the aircraft.

The primary object of the invention is to provide a cylindrical engine container capable of being made substantially air-tight and having means therein to resiliently mount an engine, particularly one including two or more mounting elements projecting laterally from opposite sides, and wherein the mounting means includes longitudinal engine bearing beams at opposite sides of the container carried on resilient devices fixed to the container wall and wherein the opposite beams are rigidly connected together by curved beam connectors extending around the engine but spaced at all points from the engine which is rigidly fixed to the engine bearing beams.

Another object of the invention is to provide a cylindrical engine container comprising a pair of similar upper and lower shells meeting along a plane including the longitudinal axis of the cylinder and having a compressible gasket at their meeting edges to exclude air and moisture from the container, and wherein means are provided in the container and attached to the lower shell to resiliently mount an engine, and wherein the mounting means include longitudinal engine bearing beams at opposite sides of the container carried on resilient devices fixed to the lower shell wall and wherein the opposite beams are rigidly connected together by curved beam connectors extending around the inside of the lower shell and spaced therefrom and wherein longitudinally extending struts extend between the curved beam connectors and are rigidly connected thereto.

Another object of the invention is to provide an engine container including an improved engine supporting structure mounted within the container and secured to the walls thereof independently of a removable cover for the container.

The above and other objects of the invention will become apparent upon reading the following detailed description in conjunction with the accompanying drawings, in which:

Fig. 1 is a side elevation view partly in section of the present jet engine container.

Fig. 2 is an end elevation view of the container.

Figs. 3, 4, 5 and 6 are transverse cross sections taken on lines 3, 4, 5 and 6 respectively of Fig. 1.

2

Considering now the principal view (Fig. 1) of the drawings, the engine container comprises a closed-end cylinder supported by a pair of floor contacting skids or rails. Means inside the container are adapted to resiliently support a horizontally disposed jet engine (not shown). Considering the drawings more specifically it will be seen that the container 1 is made of two similar semi-cylindrical shells 2 and 3. The lower shell 2 comprises a pre-shaped semi-cylindrical steel sheet welded along lines 4 and 5 to convex semi-circular end plates 6 and 7 including narrow marginal flanges integral therewith. Similarly the upper shell 3 comprises a pre-shaped steel sheet welded along lines 8 and 9 to semi-circular end plates 10 and 11 including marginal flanges extending into welded connection with the curved steel sheet extending lengthwise of the container and half-way around the container. In order to join the two shells 2 and 3 and exclude atmosphere therefrom the confronting edge portions carry angle irons 12 and 13 welded thereto (see Fig. 6), and also having a rubber or other kind of compressible gasket 14 between the superimposed flanges 15 and 16 of the angle irons. A series of threaded fasteners 17 passing through the confronting flanges 15 and 16 and gasket 14 extend all the way around the container and serve as the only connecting means between the lower shell 2 and the upper shell 3. Extending around the outside surface of each shell and welded thereto and to the longitudinal angle irons 12 and 13 are curved angle irons 18, 19, 20 and 21 which stiffen the shells. Near the top of the upper shell 3 the angle irons 20 and 21 are joined by a pair of longitudinal angle irons 22 and 23 welded securely in place. A pair of suspension rings 24 and 25 on the arch-like angle irons 20 and 21 serve to attach a lifting sling when the container is to be moved by a derrick or crane. Several cradle-like brackets, as at 26, are welded to the lower shell 2 and are also bolted onto a pair of spaced parallel longitudinal skids 27 which may be made of heavy timbers or of any other suitable material. The interior of the lower shell 2 is provided with curved stiffening plates 28, 29, 30 and 31 welded along their marginal edges. The principal stiffeners 28 to 30 are semi-circular in end elevation and are made of sheet steel having a thickness equal to that of the container walls.

Inside the container there is provided an engine supporting assembly forming the principal subject matter of the present invention. At opposite upwardly sloping sides of the shell stiffeners 28 to 30 are pairs of inverted U-shaped brackets 32,

33 and 34 welded thereon and as shown in Fig. 3 the upper horizontal bight portions thereof are apertured to receive rubber-cushioned shock absorbing supports 35. Each support 35 includes lower and upper metal attaching flanges 36 and 37 having their inner edge portions embedded in spaced rubber blocks or cushions 38 and 39. The lower flanges 36 are bolted onto the respective brackets 32, 33 and 34 and the upper flanges 37 are bolted onto the C-shaped upper brackets 40, which total six in number. Welded on top of the brackets 40 are the engine bearers 41 and 42 extending in spaced parallel relation close to the container walls at the parting line of the shells 2 and 3. As seen in Fig. 3 these beams or bearers are of box section but any one of numerous cross sectional shapes may be employed.

The shock absorbing mounts 35 may be of any standard construction but in general the mounts 35 include rubber blocks 38 and 39 of circular cross section each having a metal core therein through which passes a central draw bolt 43. The bolt which also passes through a spacer element 44 carries lower and upper cushion plates 45 and 46 which act to limit the elastic deformation of the rubber blocks 38 and 39 under stress and shock. This feature acts as a stabilizing influence to prevent excessive movement of the engine bearers 41 and 42.

The engine bearers 41 and 42 are connected by a pair of semi-circular rigidifying members 47 and 48 welded to the bearers after being notched out (see Fig. 5). The members 47 and 48 are also joined by longitudinal bars 49 to further strengthen the structure. The two engine bearers being joined together, they will tend to be displaced from their neutral position in the same direction and at the same time. Therefore, the elements attaching the engine to the engine bearers will not be ruptured as readily as would be the case if each bearer was acting independently.

Each engine bearer carries two spaced engine attaching assemblies 50 and 51, which are shown in transverse cross section in Fig. 4. The assembly 50 receives the main engine mounting trunnion on each side of the engine and located so as to approximately intersect the center of gravity of the engine. The other assembly 51 on each of the spaced engine bearers receives a secondary engine mounting bearer located toward the forward end of the engine and acting to prevent rotation of the engine about the main trunnions. The trunnion receiving assemblies each comprises a pair of spaced vertical plates 52 and 53 cut out to fit around three sides of the engine bearers and be welded thereto. These side plates are further joined together by a top plate 54 bolted down to the engine bearer by four bolts 55. The top plate 54 should be welded directly to each side plate 52 and 53. Between the side plates at the forward lower portion is a trunnion support 56 welded or otherwise secured to the side plates. The support 56 is hollowed out at 57 to receive the trunnion and a pair of threaded studs 58 project upwardly to serve as fasteners for a trunnion cap 59 having a hollowed out underside as at 60 to fit nicely over the engine carried trunnion. The principal engine attaching assembly 50 at each side of the container carries a greater portion of the engine load than the secondary assembly 51, because the main assembly is near a transverse axis passing through the center of gravity. Therefore, the principal trunnion is made heavier,

as shown by the relatively larger opening therefor in the trunnion receiving support 56.

As may be seen, the engine is supported by two trunnions on each side at diametrically-opposite points. Thus, if the engine bearing beam 41 at one side tilted slightly in one direction of relative rotation about its center as the rubber-cushioned supports flexed and the engine bearing beam 42 at the other side tilted slightly in the other direction about its center, as for instance in rough handling of the container, the resulting strain would probably break off one of the engine carried trunnions were it not for the beam connecting members 47 and 48. These connecting members eliminate or minimize the random independent movement of the engine bearing beams under shock, impact or careless handling of the container. Under movement, the engine changes from a dead weight to a live weight and failure to couple the spaced engine bearing beams will permit independent action of the beams with likelihood of breakage or deformation of the trunnion supports, trunnions and trunnion mounts on the engine casing. While I have shown only one form of rigidifying the frame extending from one beam 41 to the other beam 42, it will be understood that the connecting means may take other physical forms so long as it acts to keep the opposite beams moving in the same direction at the same time under shock and impact. It will be understood also that various resilient devices may be used to mount the engine bearing beams inside the container, for instance springs, hydraulic shock absorbers or rubber cushioned elements may be used interchangeably. The necessity for preventing failure of the engine mounting assembly will be clear, since any failure would probably damage the engine itself once the mounting assembly failed at one point and the engine actually came loose from its mounting.

The embodiment of the invention herein shown and described is to be regarded as illustrative only and it is to be understood that the invention is susceptible of variations, modifications and changes within the scope of the appended claims.

I claim:

1. A shipping container for a jet engine comprising, a lower semi-cylindrical shell and an upper semi-cylindrical shell each having semi-circular end walls and adapted to meet along a longitudinally extending medial plane to form a closed cylindrical container, means along the confronting edges of said shells to connect the upper shell to the lower shell, means attached to the lower shell to serve as container-supporting and floor-contacting elements, bracket means on opposite sides of said lower shell and rigidly attached thereto on the inside surface, resilient supporting elements mounted on said brackets, a pair of engine bearing beams at opposite sides of said lower shell and supported by said resilient supporting elements, curved bars connecting said pair of beams and having end portions rigidly connected to said beams, and a plurality of trunnion supporting devices on each of said beams spaced apart longitudinally thereof and adapted to removably retain a plurality of laterally projecting trunnions fixed on said jet engine at opposite sides thereof.

2. A shipping container for a jet engine comprising, a lower semi-cylindrical shell and an upper semi-cylindrical shell each having semi-circular end walls and adapted to meet along

a longitudinally extending medial plane to form a closed cylindrical container, means along the confronting edges of said shells to connect the upper shell to the lower shell, skid means attached to the underside of the lower shell to support the container above a floor, a plurality of bracket means on opposite sides of said lower shell and rigidly attached thereto on the inside surface, resilient supporting elements mounted on said brackets, a pair of similar parallel engine bearing beams at opposite sides of said lower shell and supported by said resilient supporting elements, curved bridging bars connecting said pair of beams and being in closely spaced relation with respect to the semi-cylindrical walls of said lower shell, a plurality of longitudinally extending struts rigidly connected between said bridging bars, and a plurality of trunnion supporting devices on each of said beams spaced apart longitudinally thereof and adapted to removably retain a plurality of laterally projecting trunnions fixed on said jet engine at opposite sides thereof.

3. A shipping container for a jet engine comprising, a lower semi-cylindrical shell and an upper semi-cylindrical shell each having semi-circular end walls and adapted to meet along a longitudinally extending medial plane to form a closed cylindrical container, means along the confronting edges of said shells to connect the upper shell to the lower shell, means attached to the lower shell to support the container above a floor, at least two curved plates mounted around the inside surface of said lower shell to reinforce the walls thereof, bracket means on the opposite sides of said lower shell and rigidly attached at opposite end portions of said curved plates, resilient supporting elements mounted on said brackets, a pair of engine bearing beams at opposite sides of said lower shell and supported by

said resilient supporting elements, curved bars connecting said pair of beams and having end portions rigidly connected to said beams, and a plurality of trunnion supporting devices on each of said beams spaced apart longitudinally thereof and adapted to removably retain a plurality of laterally projecting trunnions fixed on said jet engine at opposite sides thereof.

4. A shipping container for a jet engine comprising, a lower shell and an upper shell adapted to meet along their peripheral edges to form a closed container, means along the confronting edges of said shells to connect the upper shell to the lower shell, a plurality of bracket means on opposite sides of said lower shell and rigidly attached thereto on the inside surface, resilient supporting elements mounted on said brackets and including rubber cushioning blocks, a pair of similar parallel engine bearing beams at opposite sides of said lower shell and supported by said resilient supporting elements, curved bridging bars connecting said pair of beams and being in spaced relation with respect to the walls of said lower shell, bracing struts connected between said bridging bars, and a plurality of engine supporting brackets on each of said beams spaced apart longitudinally thereof and adapted to removably retain a plurality of projecting elements fixed on said engine at opposite sides thereof.
